COMBINED DISPLAY AND OIL DRAINING CABINET

Donald B. Goudy, 11720 Edgewater Drive,
Lakewood, Ohio

Filed Feb. 13, 1962, Ser. No. 68,799

Term of patent 14 years

(Cl. D52—2)

FIG. 4

FIG. 2

FIGURE 1 is a side elevational view of a combined display and oil draining cabinet embodying my new design, the opposite side being the same as the side shown;

The broken line representation of oil cans in FIGURE 2 is for purposes of illustration only.

I claim:

The ornamental design for a combined display and oil draining cabinet as shown and described.
